CLAIM

The ornamental design for a car tray, substantially as shown and described.

DESCRIPTION

FIG. 1 is a top plan view of a car tray, showing my new design;

FIG. 2 is a bottom plan view thereof;

FIG. 3 is a side elevational view thereof taken from the bottom of FIG. 1; the opposite side (not shown) is the mirror image thereof;

FIG. 4 is a cross-sectional view thereof taken along line 4—4 in FIG. 2;

FIG. 5 is a rear elevational view thereof;

FIG. 6 is a front elevational view thereof; and

FIG. 7 is a reduced-scale bottom perspective view thereof.
